US00D363891S

United States Patent [19]

Gough

[11] Patent Number: Des. 363,891

[45] Date of Patent: **Nov. 7, 1995

[54] MOTION DETECTION SENSOR

4,778,996 10/1988 Baldwin et al. .

[75] Inventor: **Keith A. Gough**, Prescott, England

FOREIGN PATENT DOCUMENTS

[73] Assignee: **Bridisco Limited**, London, England

484293 5/1992 European Pat. Off. .
2221984 2/1990 United Kingdom .

[**] Term: **14 Years**

Primary Examiner—Alan P. Douglas
Assistant Examiner—Antoine D. Davis
Attorney, Agent, or Firm—Nies, Kurz, Bergert & Tamburro

[21] Appl. No.: **9,973**

[57] CLAIM

[22] Filed: **Jun. 28, 1993**

The ornamental design for a motion detection sensor, as shown and described.

[52] U.S. Cl. **D10/106**

DESCRIPTION

[58] Field of Search D10/106; 340/541,
340/542, 543, 544, 545, 546, 547, 551,
571, 689; 250/338.1, 353

FIG. 1 is a top perspective view of a motion detection sensor showing my new design; and,
FIG. 2 is a bottom perspective view thereof.
